UNITED STATES PATENT OFFICE.

WILHELM BEHAGHEL AND GUSTAV CURT SCHUMANN, OF LUDWIGSHAFEN-ON-THE-RHINE, GERMANY, ASSIGNORS TO BADISCHE ANILIN & SODA FABRIK, OF LUDWIGSHAFEN-ON-THE-RHINE, GERMANY, A CORPORATION OF BADEN.

PROCESS OF MAKING INDOXYLIC COMPOUNDS.

SPECIFICATION forming part of Letters Patent No. 772,775, dated October 18, 1904.

Application filed April 12, 1904. Serial No. 202,882. (No specimens.)

To all whom it may concern:

Be it known that we, WILHELM BEHAGHEL, a subject of the Grand Duke of Baden, and GUSTAV CURT SCHUMANN, a subject of the King of Saxony, doctors of philosophy and chemists, residing at Ludwigshafen-on-the-Rhine, in the Kingdom of Bavaria, German Empire, have invented new and useful Improvements in the Production of Indoxylic Compounds, of which the following is a specification.

Our invention relates to improvements in the manufacture of indoxyl and of derivatives of indoxyl.

15 We have discovered that indoxyl or a derivative thereof is obtained when hydroxyethyl-anilin ($C_6H_5\cdot NH\cdot CH_2\cdot CH_2OH$) or an analogue or a derivative thereof (such as its carboxy derivatives or those which contain an 20 alkyl group attached to the nitrogen atom) is heated with a caustic alkali or with a mixture of caustic alkalies with or without the addition of a water-removing agent, such as an 25 alkaline oxid, or alkaline earth, or alkaline amid, or alkali metal. Instead of the free hydroxyethyl bases their alkali salts may be employed. The indoxyl or derivative thereof so obtained can be transformed in the usual manner or in any suitable manner into the 30 corresponding indigo coloring-matter.

The following examples will serve to further illustrate the nature of our invention, which, however, is not limited to these examples. The parts are by weight.

35 Example 1: Melt together one hundred and thirty-seven (137) parts of hydroxyethyl-anilin and five hundred (500) parts of caustic potash in an autoclave for one (1) hour at a temperature of from two hundred and eighty to 40 two hundred and ninety degrees centigrade, (280° to 290° C.) Dissolve in water the yellow mass so obtained and pass air through the solution and filter off the indigo which is precipitated.

45 Example 2: Heat together in an autoclave one hundred and sixty-five (165) parts of

ethyl-hydroxyethyl-anilin and five hundred (500) parts of caustic potash for one (1) hour at a temperature of from two hundred and eighty to two hundred and ninety degrees centigrade (280° to 290° C.) and work up the melt in the usual manner.

Example 3: Heat together in an open vessel provided with an inverted condenser one hundred and sixty-five (165) parts of ethyl-hydroxyethyl-anilin, three hundred and forty (340) parts of burnt lime, and three hundred and forty (340) parts of caustic potash for from one to one and a half (1 to $1\frac{1}{2}$) hours at a temperature of from two hundred and sixty to two hundred and eighty degrees centigrade, (260° to 280° C.)

Example 4: Mix together one hundred and eighty-seven (187) parts of the sodium salt of ethyl-hydroxyethyl-anilin, three hundred and forty (340) parts of lime, and one hundred and seventy (170) parts of anhydrous caustic potash and heat the whole to a temperature of from two hundred and seventy to two hundred and seventy-five degrees centigrade, (270° to 275° C.)

Example 5: Heat together one hundred and thirty-seven (137) parts of hydroxyethyl-anilin, seven hundred (700) parts of anhydrous caustic potash, and seventy (70) parts of soda-75 amid at a temperature of from two hundred and fifty to two hundred and seventy degrees centigrade, (250° to 270° C.)

Example 6: Heat together one hundred and sixty-five (165) parts of ethyl-hydroxyethyl-anilin, sixty-five parts of sodium oxid and seven hundred (700) parts of anhydrous caustic potash at a temperature of from two hundred and fifty to two hundred and seventy degrees centigrade, (250° to 270° C.)

Example 7: Melt together at a temperature of two and seventy degrees centigrade (270° C.) one hundred and eighty-one (181) parts of dihydroxyethyl-anilin, $C_6H_5\cdot N\cdot (CH_2\cdot CH_2\cdot O_2\cdot H_2)$, three hundred and sixty (360) parts of caustic 90 potash and three hundred and sixty (360) parts of quick-lime.

Example 8: Melt together at a temperature of two hundred and fifty degrees centigrade (250° C.) two hundred and nineteen (219) parts of the sodium salt of hydroxyethyl-anilin-ortho-carbonic acid and six hundred (600) parts of anhydrous caustic potash.

What we claim is—

1. The process for the production of indoxylic compounds, which consists in heating 10 an aromatic amin, which contains a hydroxyethyl group attached to the amido-nitrogen atom, in an alkaline melt.
2. The process for the production of indoxylic compounds, which consists in heating 15 an aromatic amin, which contains a hydroxyethyl group attached to the amido-nitrogen atom, in an alkaline melt containing a dehydrating agent.
3. The process for the production of indoxylic compounds, which consists in heating 20 an aromatic amin, which contains a hydroxyethyl group attached to the amido-nitrogen atom, in a caustic-potash melt.
4. The process for the production of indoxylic compounds, which consists in heating 25 an aromatic amin, which contains a hydroxyethyl group attached to the amido-nitrogen atom, in a caustic-potash melt containing a dehydrating agent.
- 30 5. The process for the production of indoxylic compounds, which consists in heating

an aromatic amin, which contains a hydroxyethyl group attached to the amido-nitrogen atom, in a caustic-potash melt containing quicklime.

35

6. The process for the production of indoxylic compounds, which consists in heating hydroxyethyl-anilin in an alkaline melt.

7. The process for the production of indoxylic compounds, which consists in heating 40 hydroxyethyl-anilin in an alkaline melt containing a dehydrating agent.

8. The process for the production of indoxylic compounds, which consists in heating hydroxyethyl-anilin in a caustic-potash melt. 45

9. The process for the production of indoxylic compounds, which consists in heating hydroxyethyl-anilin in a caustic-potash melt containing a hydrating agent.

10. The process for the production of indoxylic compounds, which consists in heating hydroxyethyl-anilin in a caustic-potash melt containing quicklime. 50

In testimony whereof we have hereunto set our hands in the presence of two subscribing 55 witnesses.

WILHELM BEHAGHEL.
GUSTAV CURT SCHUMANN.

Witnesses:

ERNEST F. EHRHARDT,
J. ALEC. LLOYD,

Correction in Letters Patent No. 772,775.

It is hereby certified that in Letters Patent No. 772,775, granted October 18, 1904, upon the application of Wilhelm Behaghel and Gustav Curt Schumann, of Ludwigshafen-on-the-Rhine, Germany, for an improvement in "Processes of Making Indoxylic Compounds," an error appears in the printed specification requiring correction, as follows: In line 49, page 2, the word "hydrating" should read *dehydrating*; and that the said Letters Patent should be read with this correction therein that the same may conform to the record of the case in the Patent Office.

Signed and sealed this 31st day of January, A. D., 1905.

[SEAL.]

F. I. ALLEN,
Commissioner of Patents.

Example 8: Melt together at a temperature of two hundred and fifty degrees centigrade (250° C.) two hundred and nineteen (219) parts of the sodium salt of hydroxyethyl-anilin-ortho-carbonic acid and six hundred (600) parts of anhydrous caustic potash.

What we claim is—

1. The process for the production of indoxylic compounds, which consists in heating 10 an aromatic amin, which contains a hydroxyethyl group attached to the amido-nitrogen atom, in an alkaline melt.
2. The process for the production of indoxylic compounds, which consists in heating 15 an aromatic amin, which contains a hydroxyethyl group attached to the amido-nitrogen atom, in an alkaline melt containing a dehydrating agent.
3. The process for the production of indoxylic compounds, which consists in heating 20 an aromatic amin, which contains a hydroxyethyl group attached to the amido-nitrogen atom, in a caustic-potash melt.
4. The process for the production of indoxylic compounds, which consists in heating 25 an aromatic amin, which contains a hydroxyethyl group attached to the amido-nitrogen atom, in a caustic-potash melt containing a dehydrating agent.
- 30 5. The process for the production of indoxylic compounds, which consists in heating

an aromatic amin, which contains a hydroxyethyl group attached to the amido-nitrogen atom, in a caustic-potash melt containing quicklime.

35

6. The process for the production of indoxylic compounds, which consists in heating hydroxyethyl-anilin in an alkaline melt.

7. The process for the production of indoxylic compounds, which consists in heating 40 hydroxyethyl-anilin in an alkaline melt containing a dehydrating agent.

8. The process for the production of indoxylic compounds, which consists in heating hydroxyethyl-anilin in a caustic-potash melt. 45

9. The process for the production of indoxylic compounds, which consists in heating hydroxyethyl-anilin in a caustic-potash melt containing a hydrating agent.

10. The process for the production of indoxylic compounds, which consists in heating hydroxyethyl-anilin in a caustic-potash melt containing quicklime. 50

In testimony whereof we have hereunto set our hands in the presence of two subscribing 55 witnesses.
